TYPE CASTING MATRIX

Application filed September 22, 1930. Serial No. 483,487.

My invention relates to type casting matrices such as used in slug type casting machines where the matrices are assembled by hand, and more particularly to means for 5 facilitating the rapidity and accuracy with which the matrices may be assembled.

Matrices for use with slug type casting machines where the matrices are assembled by hand in the casting stick are now made with 10 plane parallel abutting faces. These abutting faces gradually accumulate a deposit of foreign matter which is received from the operator's fingers. This deposit causes the matrices to stick together and thus decreases 15 the rapidity and accuracy of the operator in slipping the matrices from their respective piles in the case and assembling them in the casting stick. This foreign matter also prevents close contact between the matrices when 20 they are assembled in the casting stick, thus causing undesirable fins or flashes in the printing slugs when they are cast in the casting stick. The foreign matter also prevents free and easy alignment of the matrices in 25 the casting stick with the result that the printing faces of the printing slugs which are cast from the matrices are of uneven height and the characters are misaligned. Furthermore, this deposit causes the matrices 30 to adhere together after casting, thus interfering with their rapid separation for redistribution into their respective compartments of the case. The smooth plane abutting faces of the matrices are also objectionable 35 in that they cause the operator to exert unnecessary finger pressure in order to withdraw the matrices from the case. Furthermore, when the matrices are clamped together in the casting stick, a partial vacuum is 40 caused between the smooth abutting faces which causes adhesion and interferes with the rapid separation of the matrices for redistribution into their respective compartments.

45 All of the above mentioned disadvantages are overcome by my invention, the principal object of which is to facilitate the assembly and disassembly of the matrices. My invention consists in providing a finger grip 50 formed by holes or depressions in one or both

of the abutting faces of a matrix. With this type of construction, the foreign matter from the operator's fingers is lodged in the holes instead of on the bearing surfaces between abutting faces, and the operator is enabled 55 to withdraw the matrices from the case with the exertion of less finger pressure.

In the drawing which shows, for illustrative purposes only, preferred forms of the invention—

Fig. 1 is a side view of a type casting matrix such as used in slug type casting machines;

Fig. 2 is a central sectional view of the matrix shown in Fig. 1;

Fig. 3 is a central sectional view of an alternative type of matrix;

Figs. 4, 5, and 6 each comprise a side view and a central sectional view of alternative types of matrices.

In said illustrative drawing, 10 indicates a type casting matrix such as used in slug type casting machines. 11 and 12 represent the sides of the matrix which contact with the sides of adjacent matrices when the matrices are assembled in the casting stick. The sides 11 and 12 are spoken of in this specification as the abutting faces of the matrix. The opposite edges of the matrix are provided with positioning lugs only at or near the top 70 thereof as shown in the drawing. One or both of the abutting faces of the matrix is provided with a finger grip. This finger grip may consist of a sunken area 13 in one of the abutting faces as shown in Figs. 1, 2 and 4. If desired, finger grips may be provided on both abutting faces of the matrix, as shown in Fig. 3. The sunken area 13 may have either a flat or curved surface, preferably knurled or milled to furnish a grip with a lighter 80 touch of the finger of the operator. The surface of the sunken area may bear the characters of a trade-mark or other special design whereby roughness is secured. If desired, the finger grip may consist of a multiplicity 85 of holes which may be drilled or punched or otherwise formed and which may extend either partially or wholly through the matrix. As illustrated in Fig. 5, the holes 14 extend 90 entirely through the matrix. Or the finger 95 grip may consist of a series of depressions 100

grip may consist of a series of grooves 15, as illustrated in Fig. 6.

The use of my invention increases the coefficient of friction between the operator's fingers and the matrix and reduces the coefficient of friction between contacting matrices. The holes or indentations serve as air chambers and reduce the adhesion which is caused by the partial vacuum which is formed between abutting faces of the matrices. Adhesion between abutting faces of the matrices is also reduced by the reduction of foreign matter on the bearing surfaces. Thus rapidity and accuracy in assembling the matrices in the casting stick and in redistributing the matrices into their respective compartments are increased and the printing slugs are freed from undesirable fins and flashes and from unevenness and misalignment of the characters. Furthermore, the labor of the operator is reduced because the indentations increase the ease with which the matrices can be withdrawn from the case. Where the finger grip is provided in only one of the abutting faces of the matrix, the use of my invention automatically indicates to the operator through his sense of touch whether the matrix is in proper position or reversed, thus preventing errors arising from reversed letters.

I claim:

In a matrix for hand assembly, a matrix body with laterally extending positioning lugs adjacent the top only of said body, the central portion of the front face of said body being recessed to form a finger grip.
